(57) **CLAIM**

The ornamental design for a bedstead, as shown and described.

DESCRIPTION

FIG. 1 is a top front right perspective view of a bedstead showing my new design;

FIG. 2 is a bottom back left perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top perspective view thereof, shown in an open configuration;

FIG. 10 is an enlarged view of detail 10 in FIG. 1; and,

FIG. 11 is an enlarged view of detail 11 in FIG. 1.

The dash-dot broken lines in FIGS. 1, 10, and 11 are for the purpose of illustrating boundaries of the enlarged details shown in FIGS. 10 and 11, and form no part of the claimed design.

1 Claim, 11 Drawing Sheets
